UNITED STATES PATENT OFFICE

FRED D. HOLDSWORTH, OF CLAREMONT, NEW HAMPSHIRE, ASSIGNOR TO SULLIVAN MACHINERY COMPANY, A CORPORATION OF MASSACHUSETTS

PORTABLE COMPRESSOR OUTFIT

Application filed July 28, 1927. Serial No. 209,156.

My invention relates to portable compressor outfits.

One object of the invention is to devise an improved arrangement of the different units of a compressor outfit on a portable base frame. Another object is to provide a portable compressor outfit of very low overall height particularly adapted for use in mines where the head room is limited. A still further object is to provide an arrangement of the units in a portable compressor outfit with a view to keeping the overall width as low as possible and at the same time maintaining a minimum overall height. A more specific object is to provide a novel arrangement of the elements in a portable compressor outfit, wherein the cylinders of the compressor are positioned horizontally and transversely of the frame. Other objects and advantages will, however, hereinafter subsequently appear.

In the accompanying drawings I have shown for purposes of illustration one form which my invention may assume in practice.

25 In these drawings,—

Fig. 1 represents a plan view of the compressor outfit mounted on a mine trackway.

Fig. 2 is a vertical section through the outfit on the line 2—2 of Fig. 1, the running gear being shown in elevation.

Fig. 3 is a view in side elevation of the portable compressor outfit.

Fig. 4 is an end elevation looking from the left end of Fig. 3 and showing the mine trackway in section.

In this illustrative embodiment of my invention I have shown a frame member 1 for carrying the elements of the compressor mechanism, the frame member 1 being provided with side flanges 2 and end flanges 3. The frame member 1 has secured thereto bearing members 4, in which are mounted the truck axles 5 carrying the truck wheels 6. This construction brings the supporting level of the frame very close to the level of the axles. Other arrangements for securing the wheels to the frame element may, however, be substituted for the one which has been illustrated and described without departing from the principles of my invention. Suitable cou-

pling elements 7 may be secured to the frame in any desired manner, preferably directly to the end flanges 3. A motor 8, preferably of standard design, is secured to the floor 9 of the frame member by suitable brackets 10; 55 and is preferably positioned not midway between the sides of the frame, but offset from such a middle position. The motor shaft is, in this instance disposed longitudinally of the frame and connected directly to the crank shaft 11 of the compressor 12 through a suitable coupling element 13. If it is desired, however, to reduce the speed of the compressor below that of the motor, any suitable reduction gearing may be mounted between the motor and compressor crank shaft. The crank case 14 of the compressor has a base 15 with lugs or a flange 16 for attachment to the floor of the frame. This crank case is provided with a removable cover 17, and with means for the attachment of the compressor cylinders 18 in which the pistons 19 reciprocate. In the embodiment illustrated herein two cylinders are provided, both being arranged on the same side of the frame 1. This provides a more 70 compact arrangement than having one of the cylinders extending from each side of the crank case, which may be an important consideration if it is desired to reduce the overall width of the outfit to a minimum. However, 75

in mines where the width is not such an important consideration, the crank case may be so designed as to accommodate an extra pair of cylinders on the opposite side of the crank shaft to increase the capacity. The usual connecting rods 20 and crank shaft counterbalance weight 21 are illustrated. Air is discharged from the compressor through a line 22 to a cylindrical receiver tank 23 which is mounted alongside the motor with its longest 80 dimension extending longitudinally of the frame. As shown more clearly in Fig. 4, the receiver tank is secured to the frame by strap members 24 which have one end attached at 85 25 to a side flange of the frame and the other end attached to a member 26 which is secured to the frame by bolts 27 in the manner illustrated. The diameter of this tank is preferably limited to such an extent that it will not 90 extend above the high point on the motor, 95

but obviously the receiver tank capacity may be varied by increasing or decreasing its length, the overall length of the outfit being a comparatively unimportant matter unless curves are sharp.

5 The type of compressor illustrated is usually provided with a liquid cooling system which, in this instance, includes a low radiator 28 mounted on one end of the frame, preferably in alinement with the motor 8. The cylinders of the compressor are provided with cooling jackets 29 and if desired the cylinder heads and discharge valves may also be similarly jacketed. A small circulating pump 30 is mounted on the frame adjacent the radiator and is driven by a belt 31 from the motor shaft. This pump circulates the cooling medium from the jackets around the compressor cylinders and cylinder head through a pipe 32 to the top of the radiator, through the radiator and circulating pump, back to the compressor cylinders through the line 33. It will thus be seen that I have provided a very compact arrangement of the essential 20 units of a compressor outfit in which the overall height has been kept down to such an extent that it is determined by the high point of the driving motor when a standard motor is employed. At the same time it will be observed that the width of the entire outfit has 25 been reduced to a minimum and that any desired increase in capacity may be easily taken care of by a proportionate increase in the length of the outfit without in any way increasing the overall height or the width.

While I have in this application specifically described one form which my invention may assume in practice, it will be understood that his form of the same is shown for 30 purposes of illustration and that the invention may be modified and embodied in various other forms without departing from its spirit or the scope of the appended claims.

What I claim as new and desire to secure 45 by Letters Patent is:

1. In a portable compressor outfit, a portable base frame, a motor mounted thereon offset from a position midway between the sides of said frame with the motor shaft extending 50 parallel with the center line of the frame, a compressor connected to said motor and having a horizontal compressing cylinder extending transversely of said frame, and a receiver tank mounted alongside said motor with its longest dimension extending parallel to said motor shaft.

2. In a portable compressor outfit, a portable base frame having mounted thereon a horizontal motor, a compressor driven thereby having horizontal cylinders extending transversely of said frame, and a receiver tank mounted alongside said motor with its longest dimension extending longitudinally of said frame.

65 3. In a portable compressor outfit, a port-

able base frame, a motor mounted thereon, a horizontally disposed compressor mounted on said frame and connected to said motor, and a receiver tank mounted alongside said motor and parallel to the motor shaft, no part of said outfit projecting upwardly from said frame higher than said motor.

4. In a portable compressor outfit, a wheeled base frame movable over a trackway, a motor mounted thereon, a horizontal compressor mounted thereon having a crank shaft extending parallel to said trackway at one side of the longitudinal center line of said frame, said crank shaft being driven by said motor, and a receiver tank mounted alongside said motor with its longest dimension extending longitudinally of said frame.

5. In a portable compressor outfit, a portable base frame, a horizontal compressor mounted thereon having a crankcase offset to one side of said frame and cylinders extending horizontally transversely toward the other side of said frame, a driving motor mounted on said frame, and a receiver tank mounted on said frame wholly at the last mentioned side of the central longitudinal vertical plane of the frame, the overall dimension of said compressor in a direction parallel to the cylinders determining the overall width of the outfit.

6. In a portable compressor outfit, a wheeled base frame movable over a trackway, a motor carried thereby with its shaft extending longitudinally and offset toward one side of said frame, a compressor having a crankcase mounted on the same side of said frame as said motor and cylinders extending toward the other side of said frame, and a receiver tank mounted on said other side adjacent said motor.

7. In a portable compressor outfit, a wheeled base frame movable over a trackway, a motor carried thereby and offset toward one side of said frame, a compressor having a crankcase mounted on the same side of said frame as said motor and cylinders extending toward the other side of said frame, and a receiver tank mounted on said other side adjacent said motor, the overall height of said outfit being determined by the combined height of said motor and said wheeled base frame.

8. In a portable compressor outfit, a portable base frame having mounted thereon a motor, a compressor driven thereby having a horizontal jacketed cylinder extending transversely of said frame, a receiver tank mounted alongside said motor with its longest dimension extending longitudinally of said frame, a radiator at one end of said frame, a pump driven by said motor, and connections completing a closed cooling system including said radiator, said pump and the jacket of said compressor cylinder.

65 9. In a portable compressor outfit, a port-

able base frame having mounted thereon a motor with its shaft extending longitudinally of said base frame, a compressor driven thereby having a crank shaft extending longitudinally of said base frame and a horizontal jacketed cylinder extending transversely of said frame, a cylindrical receiver tank mounted alongside said motor extending longitudinally of said frame, a radiator at one end of said frame, a pump driven by said motor, and piping connecting said radiator and pump, said pump and cylinder jacket and said cylinder jacket and radiator.

10. In a portable compressor outfit, a wheel mounted base frame, a horizontal compressor mounted thereon having a crank shaft extending longitudinally of said frame and a horizontal cylinder extending transversely thereof, a driving motor mounted on said frame offset from a position midway between the sides thereof, and a receiver tank mounted alongside said motor, the overall dimension of said compressor in a direction parallel to the cylinder thereof determining the over-all width of the outfit.

11. In a portable compressor outfit, a wheel mounted base frame, a horizontal compressor mounted thereon having a crank shaft extending longitudinally and offset toward one side of said frame and a cylinder extending horizontally transversely thereof, a driving motor mounted on said frame having its shaft alined with said compressor crank shaft and operatively connected to drive the same, and a cylindrical receiver tank disposed longitudinally of said frame and mounted alongside said motor, the overall dimension of said compressor in a direction parallel to the cylinder thereof determining the overall width of the outfit.

In testimony whereof I affix my signature.
FRED D. HOLDSWORTH.
